UNITED STATES PATENT OFFICE.

HARRY E. ROBINSON AND DANA L. ORDWAY, OF MARLBORO, MASSACHUSETTS.

ARTICLE-HOLDER.

1,378,979.

Specification of Letters Patent. Patented May 24, 1921.

Application filed July 21, 1919. Serial No. 312,211.

To all whom it may concern:

Be it known that we, HARRY E. ROBINSON and DANA L. ORDWAY, citizens of the United States, residing at Marlboro, in the county 5 of Middlesex and State of Massachusetts, have invented a new and useful Article-Holder, of which the following is a specification.

This invention relates to an article holder, 10 for use primarily in shoe shops and other factories where many lots of shoe parts or other materials must be temporarily secured together and handled as a unit. It is the common practice to tie such lots of material 15 into packages, at a considerable expenditure of time and labor. The cord or tape required for this purpose in a large factory is also a considerable item of expense.

It is the general object of our invention to 20 provide a holder or carrier within which such articles may be temporarily secured and supported and from which they may be as readily released, all without unnecessary loss of time or waste of binding material.

25 Our invention further relates to arrangements and combinations of parts which will be hereinafter described and more particularly pointed out in the appended claims.

Two forms of our invention are shown in 30 the drawings in which—

Figure 1 is a plan view of our improved article carrier, adjustable to articles of different widths;

Fig. 2 is a perspective view of a side frame 35 member;

Fig. 3 is a perspective view of a detail part, and

Fig. 4 is a detail perspective view of a 40 second form of our invention, in which the holder is of fixed width.

Referring particularly to Figs. 1, 2 and 3, our improved article holder comprises a frame having an expandable bottom portion 10 formed of a plurality of metal strips 45 pivoted to each other as indicated, and a pair of side members 11 and 12 having slotted connections to the ends of the bottom portion 10. Each side member consists of a slotted plate 13 to which an upwardly projecting portion 14 is rigidly secured. Upper hooks 15 and lower hooks 16 are secured in the member 14 for purposes to be described.

A pair of binding chains or other flexible members 17 are secured to the hooks 15 at 55 one side of the holder, the hooks being

closed down to prevent displacement of the ends of the chains. After the articles are placed in the holder, the chains or flexible members 17 are drawn over the pile of articles, and each chain is caught under one of 60 the hooks 15 or 16 to firmly secure the articles in position in the holder.

A spring casing 17a may be attached to the free end of each chain, the casing being adapted to take up all free chain whenever 65 released, and thus prevent the chain becoming entangled with other objects.

If only a few sheets of material are to be placed in a holder, each chain may be led around a lower hook 16 before passing over 70 the articles and at the opposite side may also be secured to a lower hook 16.

In order to prevent displacement of U-shaped articles, such as the shoe vamp indicated in dotted lines in Fig. 1, we provide 75 the movable positioning device shown in detail in Fig. 3. This device consists of a wire loop 18 hinged at 19—19 to a short plate 20 which in turn is pivoted at 21 to the bottom of the frame. 80

When the device is to be used, the plate 20 is turned to the position indicated in Fig. 1 and the loop 18 is raised to stand between the separated sides of the vamps, thus retaining them in desired position. 85 When the holder is to be used for other purposes the loop may be folded down parallel with the bottom, thus permitting articles of different shapes to be retained in the holder. 90

Substantially the same general construction is shown in the form disclosed in Fig. 4, except that the frame 22 is of rigid construction. The transverse members 23 are upturned at their ends to form portions of 95 the rigid side members. The upturned ends are joined by cross bars 24, and the members 23 are braced by diagonal members 25. A positioning device 26 may be pivoted to the middle transverse member 23, substantially 100 as in the form shown in Fig. 1.

With this construction, it will be seen that articles of varying shapes and widths may be firmly secured in the holder by the chains or cords 17, and that they may be readily released therefrom. While they are within the holder, the holder and articles form a convenient unitary package which may be readily stored or handled.

It will be noticed that the spring in the 110

spring casing 17^a merely takes up the slack or loose chain and is not depended on to tension the chains over the articles in the holder.

Having thus described two forms of our invention, it will be evident that other changes and modifications can be made therein by those skilled in the art within the scope of our invention as set forth in the 10 claims, and we do not wish to be otherwise limited to the details herein disclosed, but what we claim is:—

1. An article holding device comprising two opposed rigid raised sides, a plurality of 15 bottom members forming an expansible connection between said opposed sides, the other two sides of the device being open and unobstructed, flexible binding means secured at one end to one of said rigid sides, clamping 20 means on the opposite side for detachably securing said binding means to said oppo-

site side at any point in its length, and spring take-up and storage devices for said binding means.

2. An article holding device comprising 25 two opposed rigid raised sides, a plurality of bottom members forming an expansible connection between said opposed sides, the other two sides of the device being open and unobstructed, flexible binding means secured at one end to one of said rigid sides, clamping 30 means on the opposite side for detachably securing said binding means to said opposite side at any point in its length, and an article positioning device mounted on the 35 expansible bottom and movable to operative and inoperative positions.

In testimony whereof we have hereunto affixed our signatures.

HARRY E. ROBINSON.
DANA L. ORDWAY.
